(57) CLAIM

We claim the ornamental design for a disposable or reusable serving dish, as shown and described.

DESCRIPTION

FIG. 1 is a perspective view of a disposable or reusable serving dish of the present invention;

FIG. 2 is a side elevational view thereof;

FIG. 3 is a front elevational view thereof;

FIG. 4 is a side elevational view thereof;

FIG. 5 is a rear elevational view thereof;

FIG. 6 is an enlarged bottom plan view thereof; and,

FIG. 7 is an enlarged top plan view thereof.

The broken lines in the drawings are included for the purpose of illustration and form no part of the claimed design.
